UNITED STATES PATENT OFFICE.

ARTHUR A. PREVOST, OF DETROIT, MICHIGAN.

WRENCH.

1,422,621.

Specification of Letters Patent. Patented July 11, 1922.

Application filed January 23, 1922. Serial No. 531,091.

To all whom it may concern:

Be it known that I, ARTHUR A. PREVOST, a citizen of the United States of America, residing at Detroit, in the county of Wayne 5 and State of Michigan, have invented certain new and useful Improvements in Wrenches, of which the following is a specification, reference being had therein to the accompanying drawings.

10 The invention relates to wrenches and consists in the novel construction as herein-after described.

In the drawings:

Figure 1 is a central longitudinal section 15 through a wrench;

Figure 2 is a cross-section thereof on line 2—2 of Figure 1;

Figure 3 is a top plan view.

A is one of the jaws of the wrench, which 20 is formed with a bifurcated shank B and is provided with an opening C through the jaw in alignment with the space between the furcations of the shank. D is a jaw apertured to slidably engage the shank B.

25 E is a revoluble hollow handle which has an opening to receive the shank B with the inwardly extending annular flange F for engaging notches G in the furcations of the shank. The handle E is also provided with 30 a threaded socket portion H for engaging the threaded end of a shank I insertable through the aperture C between the furcations of the shank B and attachable to the jaw D by one or more cross-connecting pins J.

The parts as above described are all simple in construction and can be manufactured by drop forging with very little machining. In assembling the wrench the jaw D is 40 first engaged with the shank B, after which the handle E is sleeved upon said shank and the furcations of the shank are sprung inward to engage the notches G with the flange F. The threaded shank I is then 45 inserted through the aperture C into engagement with the threaded socket H, after which the rectangular end of said shank I is attached to the jaw D by the pins J. When thus assembled, the jaws of the 50 wrench may be opened or closed by merely rotating the handle and by reason of the fact that the shank I fills the space between the furcations of the shank B, the latter is 55 prevented from accidental disengagement from the flange F.

What I claim as my invention is:

1. A wrench comprising a jaw member, a bifurcated shank extending therefrom and provided with notches adjacent to its end, a hollow handle member sleeved upon said 60 bifurcated shank and having an inwardly extending flange engageable with said notches when the furcations are sprung inward, said handle being also provided with a threaded socket, a jaw member sleeved 65 upon said shank member, a member insertable between the furcations of said shank member, being threaded for engagement with said threaded socket, and a cross connection between said last-mentioned member 70 and the jaw member which is sleeved upon the shank, whereby the rotation of said handle will adjust said jaw member.

2. A wrench comprising a jaw member, a bifurcated shank member extending therefrom and having notches at its end, a hollow handle member adapted to be sleeved on 75 said shank member and provided with an inwardly extending annular flange engageable with said notches when the furcations 80 are sprung inward, a jaw member slidable upon said shank member, a member insertable between the furcations of said shank to hold the same from springing inward, said member having a threaded 85 portion for engaging a threaded socket in said handle, and a cross pin for connecting said last-mentioned member with the jaw member sleeved on said shank.

3. A wrench comprising a jaw member 90 having a bifurcated shank member with an aperture through the jaw in alignment with the space between the furcations, said furcations being notched at their outer ends, a hollow handle member sleeved upon said 95 shank member having an inwardly extending flange for engaging said notches when the furcations are sprung inward and also provided with a threaded socket, a jaw member sleeved upon said shank member, and 100 a member insertable through the aperture of said first-mentioned jaw member between the furcations of said shank, said member having a threaded portion for engaging said threaded socket, and a cross pin for 105 connecting said member with the jaw member slidable upon said shank.

In testimony whereof I affix my signature.

ARTHUR A. PREVOST.
